[57] **ABSTRACT**

The cradle is mounted with respect to the apron rolls and delivery rolls such that a lap formation on the bottom delivery rolls causes the cage to automatically pivot away from the delivery rolls so as to prevent further feeding of the roving. The cradle avoids any pressure being imposed on the bottom apron which might otherwise cause breakage of the apron.

DOUBLE APRON DRAFTING ARRANGEMENT FOR SPINNING MACHINES

This invention relates to a double apron drafting arrangement for spinning machines. More particularly, this invention relates to a double apron drafting arrangement for automatically stopping drafting in response to lap formation.

In using double apron drafting arrangements it has been known to utilize a cradle for guiding the aprons into close vicinity of the nip of a pair of delivery rolls. However, the danger exists in the heretofore known arrangements in that in the case of a lap formation on the bottom delivery roll, the bottom apron is choked with increasing lap size so that the bottom apron becomes subsequently blocked. As the bottom apron roll keeps driving and as the cradle in working position is rigidly held relative to the bottom apron roll, and due to the pressure exerted on the bottom apron by the lap being formed, breakage of the bottom aprons can occur.

In order to prevent bottom apron breakage, double apron drafting arrangements have been provided with a detachable top apron cradle. In such arrangements, the cradle has been supported by the bottom apron and has been shiftable from a working position to a certain idle position and back, the bottom apron being exposed openly in this movement. A disadvantage of this known device is that in case of lap formation on the bottom delivery roll adjacent to the aprons, the top apron cradle must be turned around the longitudinal axis of the bottom apron roll and be taken off while the lap must also be eliminated. This is due to the fact that the pressure of the cradle pressure axle, still rigidly held by the support and pressure arm, against the bottom apron causes defects of the bottom apron if the process continues. Furthermore, in order to take off the cradle, a locking mechanism between the guide bridge of the top apron and the guide rail of the bottom apron must be unlocked first.

Accordingly, it is an object of this invention to create a double apron drafting arrangement with a cradle for bottom and top aprons which automatically eliminates the pressure exerted on the bottom apron if lap formation occurs on the bottom roll of the delivery roll pair following the aprons.

It is another object of this invention to automatically release the pressure between the aprons of a double apron drafting arrangement in response to a lap formation.

It is another object of the invention to pivot the cage of a double apron drafting arrangement away from the delivery rolls.

Briefly, the invention provides a double apron drafting arrangement for a spinning machine with a cradle for guiding top and bottom aprons into close vicinity of a nip of a pair of delivery rolls. This cradle is supported by the bottom apron roll and is pivotable around the longitudinal axis of the bottom apron roll from a working position to an idle position and back. In addition, the cradle which tensions both aprons is, in its working position, secured against tilting downwardly from the drafting zone plane by a support and against tilting upwardly from the drafting zone plane by a holding means. The holding means is constructed to release the cradle under a pressure exerted against the bottom apron caused by a lap formation on the bottom delivery roll so that the cradle by forcing the holding means au-

tomatically turns into the idle position if lap formation occurs.

These and other objects and advantages of the invention will become more apparent from the following 5 detailed description and appended claims taken in conjunction with the accompanying drawings in which:

FIG. 1 illustrates a cross-sectional view of a double apron drafting arrangement on a support and pressure arm with a cradle for the bottom and top aprons in 10 working position according to the invention;

FIG. 2 illustrates a cross-sectional view of the double apron drafting arrangement of FIG. 1 with the cradle for the bottom and top aprons in an idle position;

FIG. 3 illustrates a cross-sectional view of a modified 15 double apron drafting arrangement with a split cradle;

FIG. 4 illustrates a cross-sectional view of the drafting arrangement of FIG. 3 in an idle position; and

FIG. 5 illustrates a perspective view of a cradle according to the invention.

Referring to FIG. 1, a drafting arrangement for a spinning machine which is constructed as is known for drafting a roving 1 includes a pair of take-in rolls 2,3 which define a pre-drafting zone 4 with a top apron roll 6 and a bottom apron roll 7. In addition, a main drafting zone is provided in the path of the roving 1 and is defined by the apron rolls 6,7 a top apron 8, a bottom apron 9 and a pair of delivery rolls 10,11.

The bottom apron roll 7 which is a knurled roll supports a cradle 5 and drives the bottom apron 9 about a bottom apron guide rail 12 at the front part of the cradle 5 in the draft direction. The top apron 8 is driven by the bottom apron 9 and moves around the top apron roll 6 which is a pressure roll and is driven by the apron 8. Also, the top apron 8 moves around a top apron guide rail 13 at the front part of the cradle 5.

The top take-in roll 2 and the top delivery 10 are rigidly guided by pressure saddles 14, 15 respectively, saddle 14 being connected rigidly to a distributor 16 and saddle 15 to a distributor 17. The distributors 16, 17 are commonly supported via an element (not shown) in a support and pressure arm 18 by a pivot pin 19. Also rigidly connected to distributor is a middle pressure saddle 20 which in working position has a recess 21 which contacts the axle 22 of the top apron roll 6. The saddle 20 is also turnable as the distributor 17 pivots around the pivot pin 19. One double apron drafting arrangement is arranged to the right and to the left of the support and weighting arm 18. For purposes of simplicity, however, only one of the two double apron drafting systems is shown.

The pressure saddle 20 surrounds axle 22 with its recess 21 from the top and with a leg 23 at the front in the draft direction. As the axle 22 is thus secured against pivoting around the bottom apron roll 7 along a path defined by a pivoting circle 24 passing through the center of the axle 22, the cradle 5 is secured against tilting downwardly from the drafting zone plane. To the rear, the pressure saddle 20 covers the axle 22 with the recess 21 over a short distance only, ending at an end point 24 situated outside the pivoting circle 24. Furthermore, a spring hoop 25 is secured to the underside of the pressure saddle 20 and extends rearwardly therefrom parallel to the pivoting circle 24 and is bent into the draft direction below the drafting zone plane in order to take up the axle 22 as described further in the following.

If, as shown in FIG. 2, laps 26 form on the bottom delivery roll 11, a pressure is exerted against the top delivery roll 10 and against the bottom apron 9 guided into close vicinity of the nip of the pair of delivery rolls 10, 11. Owing to the upward tiltablity of the cradle 5 around the longitudinal axis of the bottom apron roll 7 the front part of the cradle 5 will turn away upwardly under the pressure exerted against the bottom apron 9 by the lap formation. While the lap on bottom delivery roll 11 increases in size and thus increasingly lifts the front part of cradle 5, axle 22 is pushed backwards with respect to the drafting direction, is forced over the end point 24 of the recess 21 in the saddle 20 and slips backwardly out of the recess 21. The axle 22 then moves along the pivoting circle 24 after slipping out of the recess 21. As the front part of the cradle 5 is lifted, the top delivery roll 10 is also lifted and turns the pressure saddle 20 around the pivot pin 19 along a pivoting circle S_D passing through the end point 24 into the direction of the pivoting circle S_A along which axle 22 turns. Axle 22 and end point 24 of recess 21 thus tangentially slide past each other in opposite directions. If a lap forms on bottom delivery roll 11, the front part of cradle 5 automatically tilts upwardly from the drafting zone plane and tears off the roving 1 between the front part of the cradle 5 and the nip of the pair of delivery rolls 10, 11. Further increase of the lap on the bottom delivery roll 11 thus is suppressed automatically.

Referring to FIG. 2, axle 22 has slipped out of the recess 21 of pressure saddle 20 completely due to the growing lap formation 26 on the bottom delivery roll 11. Cradle 5 which supports the axle 22 has pivoted backwards around the longitudinal axis of the bottom apron roll 7 and is held by virtue of the spring hoop 25 catching the axle 22. The spring hoop 25 keeps the top apron 8 which is brought into the vicinity of the take-in bottom roll 3 due to the pivoting motion of cradle 5, from contacting the take-in bottom roll 3. The supply of roving 1 to the pair of delivery rolls 10, 11 is interrupted. As axle 22 has slipped out of the pressure saddle 20, the top apron roll 6 no longer exerts pressure against the bottom apron roll 7 and the roving 1 is no longer drawn in between the top apron 8 and the bottom apron 9. The roving 1 which is still drawn in by the pair of take-in rolls 2, 3 drops onto the machine frame or onto a cover plate (both not shown) where sufficient room is available for depositing any roving material 1 still drawn in over prolonged periods until the lap is eliminated.

Referring to FIGS. 3 to 5 wherein like parts are designated with like reference characters as above, the cradle consists of a part 27 which guides the top apron 8 and of a part 28 which guides the bottom apron 9. The part 27 has, as seen in the draft direction, at the front lateral walls 29 extending downwardly and provided with recesses 32 (only one being shown). The part 27 is supported by pins 33 (only one being shown) extending outwardly from the lateral walls of the part 28 into the recesses 32. These parts 27, 28 are detachably connected at the front by the recesses 32 and the pins 33. The back, with respect to the draft direction, of guide part 27 is supported by the axle 22 of the top apron roll 6. The arrangement consisting of the two guide parts 27, 28 can pivot around the longitudinal axis of the bottom apron roll 7 as the guide part 28 is supported by the bottom apron roll 7. A spring

hoop 30, together with the spring hoop 25, is fixed to the support and pressure arm 18 by means of a holding screw 31. The spring hoop 30 surrounds the axle 22 in the front and from below with respect to the draft direction. If the pressure arm 18 is lifted, the spring hoop 30 will carry the axle 22 upwardly while the guide part 27 is lifted from guide part 28 since their connection, as mentioned above, becomes detached. The lateral walls 29 which extend downwardly, are guided by the pin 33 during the lowering of the support and pressure arm 18. In their working position, the guide parts 27, 28 are held together at the front part of the split cradle by the connecting elements mentioned before and at the back part by the pressure exacted from the pressure roll saddle 20 on the axle 22 of the top apron roll 6. In the idle position, the two guide parts 27, 28 are held together at their back parts by the spring hoop 25 receiving the axle 22 and pressing the top apron roll 6 in the direction of the bottom roll 7, whereas at their front part the aforementioned connecting elements maintain the connection (FIG. 4). The support of the pressure saddle 20 on the axle 22 in the working position corresponds to the one shown in FIG. 25. Owing to the support of the lateral guide element walls 29 on guide part 28, the split cage undergoes the same phases of movement as the cradle mentioned above in the case of lap formation on the bottom delivery roll 11. Thus, in case of lap formation, the split cradle as shown in FIG. 4 is forced over the end point 24 of the supporting recess 21 of the pressure saddle 20, automatically tilts back and the lap formation is interrupted.

The holding means for holding the cradle 5 in place until a detrimental lap formation occurs is thus constituted primarily by the pressure saddle 20 and the recess 21 with the accompanying end point 24 and secondarily by the distributor 17 and support arm 18. The spring hoop 25 serves to limit the pivoting of the cradle 5 so as not to contact the take-in rollers 2, 3.

What is claimed is:

1. In a drafting arrangement, a pair of apron rolls, a pair of aprons mounted about said apron rolls on opposite sides of a drafting plane, a cradle mounted on one of said apron rolls and supporting said aprons in tension thereon, a pair of delivery rolls adjacent said aprons, and a pressure saddle disposed to pivot about a pivot point located between the plane of said delivery rolls and the plane of said apron rolls, said pressure saddle having the other of said apron rolls disposed therein to define a working position of said other apron roll and being pivotal about said pivot point in a direction towards said delivery rolls in response to a predetermined movement of one of said delivery rolls from the other to permit said other apron roll and said cradle to pivot about said one apron roll in a direction away from said pressure saddle into an idle position, said one delivery roll being located on the same side of said drafting plane as said pressure saddle.

2. In a double apron drafting arrangement for spinning machines, the combination of a pair of delivery rolls forming a nip in a drafting zone plane; a bottom apron roll; a cradle supported on said bottom

apron roll, said cradle being pivotally mounted about the longitudinal axis of said bottom apron roll between a working position and an idle position; a top apron and a bottom apron supported and tensioned on said cradle for guiding into close vicinity to said nip with said cradle in said working position; a top apron roll having an axle mounted in said cradle; a pressure saddle surrounding said axle from above and in front with respect to the draft direction to within a pivoting circle extending through the axis of said top apron roll for securing said cradle in said working position against tilting downwardly from said drafting zone plane, and in back to an endpoint situated above said pivoting circle for releaseably holding said cradle in the working position of the drafting arrangement against tilting upwardly from said plane, said pressure saddle being pivotally connected to a support and pressure arm to pivot about a center point located between the plane passing through the axes of said delivery rolls and the plane passing through the axes of said apron rolls, said arm being shiftable upwardly with respect to said drafting zone plane whereby upon occurrence of a lap formation on the bottom roll of said delivery rolls, the lap abuts said bottom apron to simultaneously move said axle of said top apron roll past said endpoint and pivot said cradle about said longitudinal axis of said bottom apron roll into said idle position to prevent further lap formation.

3. In a double apron drafting arrangement as set forth in claim 2 further including a pair of take-in rolls and a spring hoop extending from said saddle to the drafting zone plane parallel to and above said pivoting circle, said spring hoop being fixed to said saddle and bent at the free end thereof into the draft direction to partially surround said axle of said top apron roll whereby said hoop holds said cradle in said idle position against further upward tilting and out of contact with said take-in rolls.

4. In a double apron drafting arrangement as set forth in claim 2 wherein said cradle includes a first guide part guiding said top apron and supported on said top apron roll, and a second guide part guiding said bottom apron and supported on said bottom apron roll, said guide parts being detachably connected to each other at the front with respect to the draft direction.

5. In a double apron drafting arrangement as set forth in claim 4 further including a first spring hoop connected to said support and pressure arm surrounding said axle of said top apron roll in the front and from below with respect to the draft direction, and a second

5

spring hoop extending off from said saddle to said drafting zone plane parallel to and above said pivoting circle, said second spring hoop being fixed to said saddle and bent at the free end thereof into the draft direction to hold said guide parts together in said idle position while acting in the direction of said bottom apron roll.

6. In a double apron drafting arrangement for spinning machines, the combination of a pair of delivery rolls forming a nip in a drafting zone plane, a bottom apron roll, a cradle supported on said bottom apron roll, said cradle being pivotally mounted about the longitudinal axis of said bottom apron roll between a working position and an idle position, a top apron and a bottom apron supported and tensioned on said cradle for guiding into close vicinity to said nip with said cradle in working position, a top apron roll mounted in said cradle, a support for securing said top apron roll and cradle in said working position against tilting downwardly from said drafting zone plane, and means for releasing said cradle and top roll from said support to allow tilting of said cradle upwardly from said plane under a pressure against said bottom apron exerted by a lap formation on the bottom roll of said delivery rolls, said support being pivotally connected to said means to pivot about a point located between the plane of the axes of said delivery rolls and the plane of the axes of said apron rolls towards said delivery rolls in response to the occurrence of a lap formation on said bottom delivery roll whereby said cradle is tilted into said idle position.

7. In a double apron drafting arrangement as set forth in claim 6 wherein said top apron roll has an axle supported in said cradle, and wherein said support comprises a pressure saddle surrounding said axle from above and in front with respect to the draft direction to within a pivoting circle centered in the axis of said top apron roll and in back to an endpoint situated outside said pivoting circle, and said means includes a support and pressure arm connected to said saddle, said arm being shiftable upwardly with respect to said drafting zone plane.

8. In a double apron drafting arrangement as set forth in claim 7 further including a pair of take-in rolls and a spring hoop, said spring hoop being fixed to said saddle and bent to partially surround said top apron roll whereby said hoop holds said cradle in said idle position against further upward tilting and out of contact with said take-in rolls.
